UNITED STATES PATENT OFFICE.

LOUIS FELD, OF PHILADELPHIA, PENNSYLVANIA.

ROLLER-SCREEN.

1,250,827.

Specification of Letters Patent. Patented Dec. 18, 1917.

Application filed December 11, 1914. Serial No. 878,65

To all whom it may concern:

Be it known that I, Louis FELD, a citizen of the United States, residing in Philadelphia, Pennsylvania, have invented certain 5 Improvements in Roller-Screens, of which the following is a specification.

My invention relates to roller screens, more particularly screens of the type employing a metal housing which is carried by 10 the window frame and supports a spring roller upon which the screen is wound; the material of such screen being of flexible metal or fabric and capable of being wound up upon the spring roller.

15 In the present invention, my improved screen structure comprehends a casing or housing to be attached to the window sill, and centrally mounted with respect to the lateral dimensions of the window frame; 20 such casing having end walls in which a spring roller, upon which the screen is wound, is operatively mounted. Carried by the sides of the window frame are metal guiding members receiving the edges of the 25 screen; said guiding members being double-walled throughout their length for the reception of the screen fabric, and having enlarged sockets adjacent the sill for the reception of the ends of the roller housing or 30 casing.

These and other features of my invention are more fully described hereinafter, reference being had to the accompanying drawings, in which:

35 Fig. 1, is a perspective view, partly in section, showing my improved screen in the position of use;

Fig. 2, is a sectional plan view on the line 2—2, Fig. 1;

40 Fig. 3, is a perspective view of one of the side guides, and

Figs. 4 and 5, are sectional views illustrating details of my invention.

In the drawings illustrating my improved 45 structure, 1 represents the window frame, having the usual sill or ledge 2; such frame receiving a sash 3 which is slidable therein in grooves 4 in the usual and well known manner. Mounted upon the sill or ledge 2, 50 directly in front of the sliding sash 3 and centrally disposed with respect to the lateral dimensions of the window frame, is a casing or housing 5 receiving a spring roller structure 6 upon which is mounted a section 55 of metallic or fabric screen cloth 7 sufficiently flexible as to be readily rolled upon

or unrolled from the spring roller. The housing is provided with end walls 8 and 8^a integral therewith in which the spring roller is operatively mounted, and such casing is preferably secured by means of fastening members 9 passing through the bottom of the same into the sill.

The screen or netting 7 is provided with a binding bar 10, preferably of sheet metal 65 folded so as to properly engage and bind the edge of the said netting, as more clearly shown in Fig. 5, and this binder bar is constructed for connection with the sash 3 and to move with the latter, so that when the 70 sash is opened the screen will be brought into position to cover said opening. For this purpose, it may be provided with a pair of keyhole slots 11, for engagement with hooks 11^a carried by the sash in the 75 manner clearly shown in the drawings.

In order that my improved screen may be employed with windows of varying width, I provide side guides 12 for the edges of the screen, which guides are quite wide so as to 80 receive a greater or less portion of the screen and the casing for the spring roller. These guides are attachable to the sides of the window frame and are provided with enlarged portions or sockets 13 to receive the ends of 85 the roller housing.

It will be noted that the roller housing 5 is complete in itself having end walls 8 and 8^a in which the roller is operatively mounted; the wall 8 being apertured to receive 90 the spindle 6^a, while the wall 8^a is slotted to receive the squared tensioning shank 6^b.

The side guides 12 comprise double-walled metal strips; the walls 12^a of which are spaced apart for the reception of the edges 95 of the screen, while said double walls are doubled back at the rear to provide a flanged portion 14 whereby they may be secured to the side of the window frame; such portion being perforated or apertured at 15 for the 100 reception of fastening means in the nature of screws, nails, &c., 16, while the lower ends of said side guides are enlarged to form the sockets 13 for the reception of the ends of 105 the roller screen housing.

By disposing such housing centrally with respect to the window sash, it is possible to employ one size structure with a number of different width windows; increase or decrease in width of the structure necessary 110 to fill the window space being taken care of by the wide walls of the side guides.

My improved structure is neat in appearance, takes up but little room, is strong, and is highly efficient for the purpose for which it is intended.

5 In mounting my improved screen structure in a window, the casing and side guides are assembled together and placed upon the window sill between the sides of the frame. The casing is then centrally disposed with 10 respect to the frame and secured to the sill, and then the side guiding members are moved outward until they contact with the sides of the frame. After this, the binding bar at the free end of the screen material is 15 connected to the bottom rail of the lower sash and the screen is ready for use. The screen is preferably fitted when the sash is in place.

While I have shown and described my improved window screen for use in the lower part of the window, it will be understood that it may be used at the upper part of the window without departing from my invention.

25 I claim:

1. In a window screen structure, the combination with a window frame and a sliding sash therefor, of a sheet metal housing mounted in fixed position on the sill thereof and disposed substantially centrally between the sides of said window frame, said housing having end walls integral therewith, a spring roller inclosed by said housing and operatively mounted in said end walls, double-walled guides of sheet metal carried by the sides of said window frame independently of the housing, a section of flexible foraminous material carried by said spring roller with its lateral edges adapted 35 to lie between the walls of said guides; the latter being enlarged at their lower ends to adjustably receive the ends of the screen-roller housing and being of appreciable width whereby their position on the window frame with respect to the housing and the section of foraminous material renders the 40 screen structure adaptable to windows of varying width, said foraminous material having its free end removably secured to the

sliding sash whereby it may be raised and 50 lowered therewith.

2. In a window screen structure, the combination with a window frame and a sliding sash therefor, of a non-extensible sheet metal casing open at one side and provided 55 with a base portion adapted to be secured to the sill of the window frame centrally with respect to the sides of the same; said casing having end walls integral therewith, a spring roller arranged to revolve within the casing and operatively supported in said end walls, double-walled guiding members of sheet metal and of appreciable width secured to the sides of the window frame and having enlarged lower portions to receive 60 the ends of the roller casing, and a continuous sheet of screen fabric carried by the spring roller and having its free end removably secured to the sliding sash to be raised and lowered therewith.

3. In a window screen structure, the combination with a window frame and a sliding sash therefor, of a non-extensible sheet metal casing open at one side and provided with integral end walls and a base wall 7 adapted to be secured to the sill of the window frame, a spring roller mounted to revolve freely within said casing and operatively supported in said end walls, a continuous sheet of open mesh fabric carried by the roller and having its free end removably secured to the sliding sash to be raised and lowered therewith, and double-walled side guides of sheet metal and of appreciable width fixed to the sides of the window frame for receiving the edges of said open mesh fabric; said guides having enlarged lower ends for the telescopic reception of the ends of the screen-roller casing.

In testimony whereof, I have signed my name to this specification, in the presence of two subscribing witnesses.

LOUIS FELD.
